UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

SOLE MACHINE.

Application filed March 22, 1926. Serial No. 96,563.

This invention relates to sole machines and more particularly to such machines employed in the manufacture of lipped insoles for shoes. As herein illustrated, the invention 5 is embodied in a machine which, by a simple interchange of parts, is adapted for use both in pressing together the flaps of a channeled insole to form a stitch-receiving lip or rib and also for applying reinforcing fabric to 10 one face and against the lip of a lipped insole. Usually an adhesive will be applied to the appropriate portions of the insole or fabric before they are presented to the machine for either of said operations. As already 15 suggested, the machine when fitted for either of these two operations may be changed over to adapt it for performing the other operation in a simple manner and in a relatively short time.

20 The object of the present invention is to improve the construction and mode of operation and to facilitate the adjustment of machines of the general type above described, to increase the durability of such machines 25 and to reduce the time and attention required for maintaining them in successful and efficient operation.

Accordingly, for the accomplishment of that and other objects, the present invention 30 comprises certain novel combinations and arrangements of parts which will now be described in detail in connection with the accompanying drawings which illustrate the preferred embodiment of the invention with the parts needed for performing both operations above referred to and the invention 35 will then be particularly pointed out in the appended claims.

In the drawings:

40 Fig. 1 is a front elevation partly in section of the machine as fitted for reinforcing insoles, the lower portion of the machine being omitted;

45 Fig. 2 is a plan view also partly in section with the right end portion of the machine omitted;

Fig. 3 is an end elevation, upon a larger scale, of the head of the machine, a small portion of it being shown in section;

50 Fig. 4 is a perspective view of the head of the machine with the front section of the head and the parts carried thereby removed;

Fig. 5 is a similar view of the principal op-

erating parts of the machine with a portion of a sole shown in working position; 55

Fig. 6 is a front sectional elevation of the principal operating parts shown as acting upon an insole;

Figs. 7 and 8 show respectively in side and end elevation a special form of the feed or 60 canvas roll;

Fig. 9 is an end elevation of the machine as fitted for the lip pressing operation, and

Fig. 10 is a sectional elevation, similar to Fig. 6, also showing the machine as fitted for 65 lip pressing.

Referring particularly to Figs. 1 to 6, the work engaging tools include a pair of feed rolls 20, 22 and a work positioning or pressure roll 24 which functions also as a feed 70 roll. These rolls may have the shapes and relative arrangement which are clearly shown in Fig. 6. The roll 20 is shaped to engage the reinforcing fabric or canvas R and press it progressively, lengthwise of the 75 lip, into the angle formed between the body of the insole S and the lip formed by uniting the two flaps L, L', as will be further explained in connection with Figs. 9 and 10.

The lower feed roll 22 is shaped to engage 80 the outer side of the lip L, L' and also the feather F of the insole while the pressure roll 24 has the general shape of a double truncated cone and the bulging portion of this roll engages the unlipped surface of the 85 insole at a point substantially opposite the lip and substantially opposite the space between the rolls 20, 22. Under usual conditions, these three rolls are positively driven to rotate at substantially the same peripheral 90 speed but the relative speed and the shapes of the rolls may be modified to suit different

kinds of work and different working conditions, as will be further explained. The upper feed roll 20 is formed on the end of a 95 removable section of a horizontal shaft 26 rotatable but fixed longitudinally in bearings in a carrier 28 which has a limited rocking movement upon a shaft 30 which is located heightwise between the axes of rolls 20 and 22 and is rotatable in bearings of brackets 31 extending inwardly from a removable housing 32 forming the front section of the head of the machine. With this construction, the roll 20 in its movement 100 toward and from the roll 22 travels approxi-

- mately in the vertical plane determined by the axes of said rolls and the axes of the rolls are maintained parallel in all positions of the rolls.
- 5 In order to provide for ready adjustment longitudinally and complete removal of the roll 20 and its section of the shaft, the latter is slotted, as indicated at 33 in Fig. 2, and a screw 34 passes therethrough and through 10 a split spring collar 35 (see also Fig. 5) loosely surrounding the shaft and threaded to receive the lower end of the screw. By tightening the screw the collar may be clamped to the shaft, thus firmly holding it 15 and its roll in the longitudinal position to which they have been adjusted by the operator. A joint 36 permits a slight relative movement between the two sections of the shaft 26 while maintaining their driving connection.
- 20 As shown in Fig. 3 the carrier 28 is provided with an extension 37 normally pressed against an adjustable stop 38 by a spring 40 the force of which may be adjusted by a screw 42. The 25 housing 32 and also the corresponding housing at the rear of the machine, to be described, are constructed and mounted for ready removal from the machine so that the various parts may conveniently be inspected, adjusted 30 or exchanged. To that end the housing 32 is provided near its lower end with holes which have a sliding fit over studs 44 to which the housing may be clamped in its proper position by set screws one of which is shown at 46.
- 35 The feed roll shaft 26 has secured to its rear end, as shown in Fig. 5, a pinion 50 driven through an intermediate gear 52 by a gear 54 secured to the shaft 30. Another gear 56 (Fig. 2) secured to the shaft 30 meshes with a gear 58 fast to the main shaft 60 of the machine. 40 At the front end of this shaft 60 the feed roll 22 is secured by a screw 62 threaded into the reduced end 64 of the shaft. As shown in Fig. 6, this reduced portion of the shaft has 45 also secured to it a canvas clearing wheel 68 with peripheral teeth 70, this wheel being spaced, however, from the rear face of the feed roll 22 to permit the entrance of the canvas trimming knife, as will be later explained.
- 50 The pressure roll 24 is securely held in adjusted position at the upper end of its vertical driving shaft 72 by expanding the hollow, split, upper end 74 of the shaft through the action of a screw 76 threaded into the 55 hollow end of the shaft and having a conical portion 78. The shaft 72 is rotatable in a carrier 80 being driven by a bevel gear 82, secured to the shaft, which meshes with a gear 84 secured to a horizontal shaft 86 which in 60 turn carries a gear 88 having relatively long teeth to mesh with a gear 90 secured to the shaft 60. The shaft 86 is carried by and longitudinally movable with a non-rotatable sleeve 92 forming a part of or rigidly secured 65 to the carrier 80. To this sleeve may be clamped a block 93 from which extends laterally a steady pin 94 fitting a hole 96 in the frame of the machine. Thus, the carrier 80 and the parts carried thereby may be adjusted both angularly about the axis of the shaft 70 86 and also longitudinally with respect to the rolls 20, 22 and then securely held in adjusted position by tightening the clamping screw 98 and thus clamping the block 93 to the sleeve 92. Accordingly, the pressure roll 24 is compelled to move in a straight line, generally perpendicular to the axis of the pressure roll, in its movement toward and from the other rolls and, therefore, it occupies the same vertical relation to the roll 22 in all of its positions and when operating on soles of different thicknesses. Moreover, when the screw 98 is loosened and the block 93 unclamped from the sleeve 92, the carrier can be adjusted angularly to vary the "lead" of the roll 24, i. e. its 75 80 85 relation along the line of feed with respect to the other rolls, as is sometimes desirable under specific operating conditions. The tightening of screw 98 will secure the roll 24 in such adjusted position. As illustrated in 90 Figs. 1 and 4, the block 93 is provided with a slot 104 in which is slidable a block 106 carried by an arm of a lever 108 which is pivoted upon one of the rods 44 already referred to. A spring 110 is interposed between the head 112 of the machine and a lug 114 projecting downwardly from the lever 108. An adjustable stop 116, passing through a forwardly extending bracket 118 of the head 112 in position to engage the lug 114, limits the inward 95 movement of carrier 80 and its roll 24 under the influence of spring 110. As shown in Figs. 1 and 3 the lever 108 has an arm 120 connected to a treadle (not shown) through a rod 122, lever 124, and treadle rod 126. By depressing the treadle rod the pressure roll 24 is moved in a straight line directly away from the feed rolls 20, 22. During this movement the carrier 28 and the feed roll 20 are lifted away from the lower feed roll 22 through connections including an adjustable screw 128 100 threaded into lever 108 and engaging a vertical rod 130 sliding in a hole in the head 112 of the machine and engaging the lower side of the carrier 28. By adjusting screw 128 105 the precise timing of the movements of the pressure roll 24 and the feed roll 20 with relation both to each other and to the lower feed roll 22 can be varied as desired and especially when feed rolls of different sizes are 110 substituted as, for example when changing the parts as required to adapt the machine to operate on soles for men's rather than women's shoes. Normally the adjustment will be such that roll 20 will operatively engage the work 115 slightly before roll 24 does in order to secure the best quality of work.
- To facilitate placing the sole S initially with its lip L, L' and the reinforcing fabric R in proper relation to the feed rolls and to 120 125 130

maintain such relation throughout the operation of the machine thereon, several gages or guides are provided some or all of which may be utilized upon any particular kind of sole 5 according to its special characteristics and other operating conditions. For example, different gages will often be employed for soles for men's, as compared with women's, shoes. As shown particularly in Fig. 4 there 10 is provided in advance of the lower feed roll 22 a guide or guard 138 which is located to engage the sole in the vicinity of the outside angle of the lip. This guide is clamped in a block 140 having a cylindrical stem 142 which 15 may be adjustably clamped in the head of the machine by a screw 144, the guide 138 being secured in adjusted position in the block 140 by a set screw 146.

For the purpose of maintaining the sole at 20 the desired angle, for example with relation to the end face of the tool 20, as shown in Fig. 6, there is provided a sole guide 148 which may be clamped in a block 150 by a set screw 152 (Fig. 4), the block 150 being provided with a rearwardly extending stem 154 which may be adjusted angularly and longitudinally and then clamped in adjusted position in the head 112 by a set screw 156. Another guide 160, shown for example in Fig. 30 5, is mounted to bear upon the unlined surface of the sole just in advance of the pressure roll. This guide may be clamped in a block 162 by a set screw 164 and has a depending stem 166 which may be adjusted in the carrier 80 and then clamped by a set screw 168. All three of these guides or gages are thus mounted for adjustment in three directions to meet varying operating conditions but it is to be understood that upon certain kinds of 35 work, with different operators and under other operating conditions it may be unnecessary to make use of some of these adjustments and, indeed, in some cases equally good work can be done without using some of these 45 guides at all and particularly the guide 160. These guides also function to some extent as guards to prevent the operator's fingers or clothing from being drawn between the feed rolls.

50 As illustrated, the machine is provided with means for trimming the margin M of the canvas flush with the top of the lip L, L' or trimming both said margin and the lip, as shown in Fig. 6. The trimming means shown 55 comprises a disc knife 174 which, as indicated in Fig. 2, is removably secured to the end of a horizontal shaft 176 which is engaged by spring actuated plunger 178 to cause the outer face of the knife 174 to be pressed firmly 60 against the inner face of the feed roll 22. A movable guard 179 for the knife is fixed to a pin 172 (Fig. 4) which is slidable and rotatable in a part of a housing 193 and which may be clamped in desired position by a set screw 65 173. The knife shaft 176 rotates in a rock-

ing lever or frame 180 (Fig. 3) pivoted on a stud 181 clamped in the housing 193 and having an extension 182 engaged by an adjusting screw 183 which may be turned to rock the lever 180 and thus move the knife and its 70 shaft toward and from the axis of the feed roll 22. The lever 180 may be clamped in adjusted position by manipulating a screw 184 which bears against a slide 185 having a surface 186 complementary to a cylindrical surface of the fixed stud 181. By tightening the screw 184 the lever 180 will be clamped firmly to the stud 181 and the knife 174 will be maintained in the desired overlapping relation to the feed roll 22. The 80 knife shaft 176 is rotated at high speed by connections comprising gears 187, 188 and 189 (Fig. 3), the latter being mounted on a shaft 190 (Fig. 2) which is in line with the stud 181. Shaft 190 also carries a gear 191 meshing with 85 a gear 192 on a clutch member 232 to be described. Shaft 190 is mounted in bearings projecting from a housing 193 which is complementary to the housing 32 referred to above and which like the latter is readily removable from the machine, being supported upon rods, one of which is shown at 194, and clamped in adjusted position by screws such as 196.

Inasmuch as the layer of canvas R is 95 united to the sole by an adhesive which is in sticky condition while the sole is passing through the machine, it is desirable to supply oil to the feed roll 20 and to the canvas clearing wheel 68 to prevent the canvas 100 from adhering to the machine parts. This oil may be supplied from a cup 198 to the roll 20 and to a felt pad 200 below the roll and in contact with the clearing wheel.

For conveniently sharpening the knife, a 105 grinding wheel 208 is so mounted that it may be readily moved from inoperative position shown in Fig. 4 into operative position where it engages the rear face of the knife 174, as shown in Fig. 3. The grinding wheel is 110 mounted upon a shaft 210 which is freely rotatable in a bearing 212 carried by a bracket 214 having a handle 216, the bracket being pivoted upon a shaft 218 rotatable in the housing 193. A spring 220 surrounding 115 the shaft 218 tends constantly to turn the grinding attachment into its inoperative position shown in Fig. 4. It will be noted that the axis of the grinding wheel 208 does not intersect the axis of the knife 174 and, 120 because of the angular relation of these parts at the point or points of contact where the tangents to the circles of the wheel and knife are at an acute angle, the grinding wheel is 125 caused to turn comparatively slowly by reason of its engagement with the knife. As the grinding wheel is reduced in diameter by wear the bearing 212 and the wheel 208 may be adjusted in a direction perpendicular to the axis of shaft 210 by means of an adjust- 130

ing screw 222 the head of which engages a slot in a longitudinally-movable non-circular rod 224 which carries the bearing 212. 226 indicates a sheet metal guard for the grinding wheel.

For driving the main shaft 60 and the parts connected therewith, there is provided a clutch member 230 (Fig. 1) which is keyed to the shaft 60 and which may be shifted 10 into frictional engagement with a co-operating clutch member 232, freely rotatable but not movable longitudinally, upon shaft 60.

A gear 236 upon the clutch member 232 is driven through gears 238, 240, 242 and 244 15 from a vertical shaft 246 in the column 248 in the machine. Conveniently this shaft 246 may be driven by an electric motor in the base of the machine. The engagement of the two clutch members 230, 232 may be controlled in the usual manner through a spring and a treadle (not shown) which actuate a treadle rod 250, a lever 252 and a block 254 20 slideable with member 230 on shaft 60. It will be observed that gear 192 and knife 174 are driven continuously at a high, uniform speed even when, through relative slip permitted between, or disengagement of, clutch members 230, 232, the feed rolls are driven 25 at slow speed or are at rest. From the practical standpoint, this arrangement is 30 advantageous because the cutting action of the knife is then equally effective whatever the rate of feed of the work, for example at the toe of the sole where that feed may be slow.

35 Supports for the soles before and after they are operated upon by the machine are shown at 260 and 262. A scraper 264 and a chute 266 conduct the trimmed material to a receptacle 268.

40 Under usual conditions a roll 20 with a circular end face does entirely satisfactory work but the form of roll 20^a shown in Figs. 7 and 8 may be preferred because the acting edge 21^a is polygonal with rounded corners 45 and tends to force the canvas R more firmly into the angle of the lip.

45 Figs. 9 and 10 illustrate the machine when equipped with substitute fittings adapting it, as above described, for the operation of 50 pressing together the two flaps L, L' preparatory to the application of the reinforcing fabric. As is customary for this lip pressing operation, the surfaces of the flaps which are to be united are previously provided with an adhesive and are then consolidated into a unitary stitch receiving lip or rib as they are progressively turned up from the body of the insole and pressed together. For this purpose, instead of the 55 housing 193 carrying the canvas trimming knife 174, there is mounted in the machine a similar housing 193' suitable for the lip setting operation which requires no trimming mechanism and consequently no grinding attachment. Moreover, preferably the

feed rolls shown in Fig. 6 are replaced by cylindrical feed rolls 20', 22' and 24' of the shapes and sizes indicated in Fig. 10. Furthermore, the guides 138 and 148 are replaced by plows 138' and 148' which are inserted beneath the flaps lying initially close to the body of the sole as shown at the top of Fig. 10 and which progressively raise them toward each other for the action of the feed rolls 20', 22' which press the lips together to form a unitary lip, as already described.

50 As shown in Fig. 9, not only is a guide 160', similar to guide 160, provided on the entrance side of the feed rolls but a corresponding guide 160'' is provided on their exit side.

55 Fig. 9 also best illustrates hollow bosses 261 which are integral with and extend inwardly from the housings 32, 193 and 193' 85 and the ends of which bear against a central portion 263 of the machine frame and thus locate the housings in their proper position in the machine. The housings are further clamped in place by bolts 265 threaded into 90 said portion 263 of the frame and by a connecting link 267 pivoted to housing 32 and held by a set screw 269 in housing 193 or 193'.

60 Having thus indicated the object and nature of the invention and having described in detail a machine embodying it, what I claim as new and desire to secure by Letters Patent is:—

65 1. A machine for operating on lipped soles 100 having, in combination, a pair of substantially parallel, horizontal shafts, a pair of feed rolls to engage opposite faces of the lip and being secured to the respective shafts, a vertical shaft, a pressure roll to engage the unlipped face of the sole opposite the lip and being secured to said vertical shaft, a driver and connections therefrom to all of the said shafts constructed and arranged to rotate the rolls in a predetermined speed ratio, supporting means for said shafts including a movable carrier for the vertical shaft, and means for compelling movement of said carrier with relation to the pair of rolls to be in a straight line perpendicular to the axis of the vertical 115 shaft.

70 2. A machine for operating on lipped soles having, in combination, a pair of rolls to engage opposite faces of the lip and being rotatable about substantially parallel axes, a 120 pressure roll to engage the unlipped face of the sole opposite the lip and being rotatable about an axis substantially perpendicular to said axes, guiding and supporting means for all of said rolls which permits the rolls of said pair to move relatively toward and from each other and compels any movement of the pressure roll toward or from the other rolls to be in a straight line perpendicular to the axis of the pressure roll, and driving means in- 125

cluding an axially slidable shaft operatively connected to the pressure roll for actuating all of the said rolls.

3. In a machine for operating on lipped soles, a frame, in combination with sole feeding mechanism comprising a pair of rolls to engage opposite faces of the lip, a pressure roll to engage the unlined face of the sole, a movable carrier, a shaft in the carrier to 10 which said pressure roll is secured, a sleeve connected to said carrier and constructed and arranged to slide rectilinearly in said frame, means to maintain said sleeve and carrier in predetermined angular position in the frame, 15 a shaft slidably with the sleeve and operatively connected to the carrier shaft, and means carried by the frame for driving said slidable shaft in its various positions.

4. A machine for operating on lipped soles 20 having, in combination, a pair of rolls to engage opposite faces of the lip and being rotatable about substantially parallel axes, a pressure roll to engage the unlined face of the sole opposite the lip and being rotatable about 25 an axis substantially perpendicular to said axes, and guiding and supporting means for all of said rolls which permits the rolls of said pair to move relatively toward and from each other but maintains the axes of said pair of 30 rolls parallel in all positions thereof and compels the movement of the pressure roll toward and from the other rolls to be in a straight line.

5. A machine for operating on lipped soles 35 having, in combination, a pair of feed rolls rotatable about parallel axes and adapted to engage opposite faces of the lip of a sole, a pressure roll to engage the unlined face of the sole opposite the lip, and guiding and supporting means for said rolls which permits the rolls of said pair to move relatively toward and from each other but maintains their axes parallel in all positions thereof.

6. In a machine for operating on lipped soles, the combination of a pair of rolls to engage opposite faces of the lip, a pressure roll to engage the unlined face of the sole, and guiding and supporting means for the rolls which permits movement of each of the three 50 rolls relative to the others but maintains their axes always in the same angular relation in their different relative positions.

7. In a machine for operating on lipped soles, the combination of a pair of rolls to engage opposite faces of the lip, a pressure roll to engage the unlined face of the sole, guiding and supporting means for the rolls which maintains their axes always in the same angular relation, means acting normally 60 to press two of the rolls yieldingly toward the other roll, and means movable by the operator for moving said two rolls away from the other roll.

8. In a machine for operating on lipped soles, the combination of a plurality of rolls

for supporting and feeding a lipped sole and sole positioning and guiding devices including a normally stationary guide constructed and arranged to engage the face of the sole at a substantial distance from and within the lip, and means by which the guide may be adjusted horizontally, vertically and angularly and then clamped in adjusted position.

9. A machine for operating on lipped soles 75 having, in combination, a pair of rolls to engage opposite faces of the lip of a sole, a pressure roll having a bulging periphery to engage the unlined face of the sole opposite the lip, and sole positioning and guiding devices 80 including a normally stationary guide constructed and arranged to engage the lipped face of the sole at a substantial distance from and within the lip and to bend the sole over said bulging periphery, and means by which 85 the guide may be adjusted horizontally, vertically and angularly and then clamped in adjusted position.

10. A machine for operating on lipped soles having, in combination, a pair of rolls 90 to engage opposite faces of the lip, a pressure roll to engage the unlined face of the sole opposite the lip, and sole positioning and guiding devices including three guides normally stationary with relation to the respective rolls 95 but capable of independent adjustment.

11. A machine for operating on lipped soles having, in combination, a pair of rolls to engage opposite faces of the lip, a pressure roll to engage the unlined face of the sole 100 opposite the lip, and means for supporting said pressure roll constructed and arranged to permit adjustment of said roll in the direction of the feed of the sole.

12. A machine for operating on soles having, in combination, a pair of rolls to engage opposite faces of the work, means for rotating said rolls, a disc knife co-operating with one of said rolls, means for rotating the knife, and means by which the axis of the knife may 110 be adjusted transversely with relation to the axis of the co-operating roll.

13. A machine for operating on lipped soles having, in combination, a pair of substantially parallel, horizontal shafts, a pair 115 of rolls to engage opposite faces of the lip and being secured to the respective shafts, a disc knife co-operating with one of said rolls, a shaft to which said knife is secured and which is substantially parallel to the said horizontal 120 shafts, a movable support for said knife shaft, means by which said support may be adjusted to vary the distance between the axis of the knife and the axis of the co-operating roll, and means for driving all of said shafts.

14. A machine for operating on lipped soles having, in combination, a pair of substantially parallel, horizontal shafts, a pair of feed rolls to engage opposite faces of the lip and being secured to the respective shafts, a 130

disc knife, a shaft to which said knife is secured and which is substantially parallel to said horizontal shafts, means for yieldingly pressing one face of the knife against one face 5 of one of the rolls, an adjustable, pivoted support for said knife shaft, a main driving shaft, and positive driving connections from said main driving shaft to said horizontal shafts and to the knife shaft arranged to drive 10 the knife at a higher peripheral speed than the speed of the co-operating roll.

15. In a machine for operating on soles, the combination of sole feeding means, mechanism including a friction clutch through 15 which said means may be driven at variable speeds, a rotary knife for trimming material from the sole while the latter is being fed, and means for actuating said knife continuously at a uniform speed.

20. 16. In a machine for operating on soles, the combination of a pair of feed rolls, a rotary knife for trimming material from a sole while the latter is being fed, a clutch comprising a member constantly driven from a 25 source of power and operatively connected to said knife and a cooperating driven member operatively connected to said feed rolls, and means through which said clutch members may be operatively connected and 30 disconnected.

17. In a machine for operating on soles, the combination of sole feeding mechanism, a disc knife co-operating with an element of said mechanism to trim material from the 35 sole, a rotatable grinding wheel constructed and arranged to operate upon the marginal portion of said knife, and a support for the wheel movable toward and from the knife.

40. 18. In a machine for operating on soles, the combination of sole feeding mechanism, a disc knife co-operating with an element of said mechanism to trim material from the sole, and a freely rotatable grinding wheel constructed and arranged to operate upon 45 the marginal portion of said knife and bearing such relation to said knife that the respective tangents to the circles of the wheel and the knife at the point of contact are at an acute angle.

50. 19. In a machine for operating on soles, the combination of a feed roll, a disc knife co-

operating with said roll to trim material from the sole, means for rotating the knife and the roll, means for yieldingly pressing the knife against the side of the roll, a grinding wheel, and means supporting the grinding wheel for movement into and out of engagement with the marginal portion of the knife so arranged that as it comes into engagement with the knife it tends to press the knife against the 60 roll.

20. In a machine for operating on soles, the combination of a pair of feed rolls, a disc knife co-operating with one of said rolls to trim material from the sole with a shear cut, means for rotating the knife and the roll so as to cause the knife to travel at a higher peripheral speed than the roll, means for yieldingly pressing the knife against the side of the roll, a grinding wheel freely rotatable 70 about an axis which does not intersect the axis of the knife, means supporting the grinding wheel for movement into and out of engagement with the marginal portion of the knife so arranged that as it comes into engagement with the knife it tends to press the knife against the co-operating roll, and means by which the grinding wheel may be adjusted to shift the path of said movement 75 to compensate for wear of the wheel and 80 knife.

21. In a machine for operating on insoles, the combination with a pair of substantially parallel horizontal shafts, of a vertical shaft, 85 a plurality of sets of adjustable work guide supports, all of said shafts being constructed and arranged to receive interchangeably and drive different sets of feed rolls and said guide supports being constructed and arranged to receive interchangeably and hold 90 in adjusted position corresponding sets of work guides and said different sets of rolls and guides being respectively shaped for operating on an insole to press together the flaps of a channeled insole to form a stitch 95 receiving lip and to apply a reinforcing fabric to one face and against the lip of a lipped insole.

In testimony whereof I have signed my name to this specification.

FREDERIC E. BERTRAND.
